FLUID MOTOR

Vernon E. Anderson, Basehor, Kans.

Application January 15, 1951, Serial No. 206,081

3 Claims. (Cl. 121—78)

1

This invention relates to an improvement in fluid motors and more particularly to the construction thereof.

Heretofore numerous fluid motors have been designed with complicated members and intricate valve mechanism that make them inefficient and too expensive to build.

An object of the present improved invention is to provide an economical design having a ring plate with an annular channel shaped ring, the annular channel shaped ring opening toward, and being closed by, the ring plate, the ring plate being provided with intake and outlet ports, valves fulcrumed on the ring plate to open and close and inlet ports, the valves when opened dividing the annular channel shaped ring into sections or compartments, fluid impeller ribs or vanes dividing the annular channel shaped ring into sections or compartments, and cam arms on the valve fulcrum members actuated by cams on the rotatable channel shaped ring to close the valves on the intake ports when the ribs or vanes pass over the intake ports, the valves being normally opened by fluid pressure.

Another object of the present improved invention is to provide an annular channel shaped ring member opening toward a flat ring member and being closed thereby, fluid impeller vanes, an inlet port, an outlet port, the ports being in the flat ring member, a cam mounted on the annular channel shaped ring member to close the inlet valves, the inlet valves being normally opened from pressure from the fluid flowing through the inlet port and the annular channel shaped ring member being rotatable on the flat ring member by fluid pressure.

Another object of the present improved invention is to relieve shocks between the rotating shaft and the annular channel shaped ring member by having resilient spring members to form spokes from a hub on the shaft to the annular channel shaped ring member.

Another object of the present improved invention is to provide a fluid motor with few wearing parts, the valve being hinged to the flat ring member to swing into the channel shaped member without rubbing the walls thereof and acting as a head to propel ribs or vanes transversely arranged in the annular channel shaped ring member, the clearances of the parts being very small.

Another object of the present improved invention is to provide a cam member on a ring member to actuate the inlet valve to a rotatable impeller.

2

With these objects in view the invention will be more fully understood from the accompanying drawing, the following specification and the scope of the appended claims.

5 Figure 1 is a plan view of the fluid motor.

Figure 2 is a cross section in elevation taken on line 2—2 of Figure 1.

Figure 3 is a fragmentary view in elevation of the annular channel shaped ring with the inlet 10 valves projected therein and the cam and an impeller vane approaching the inlet valve.

Figure 4 is a fragmentary view similar to Figure 3 with the exception that the cam has passed over the inlet valve cam lever and closed the 15 inlet valve against the inlet port, the transverse impeller rib in the annular ring being illustrated near the rear end of the cam for different valve timing.

Figure 5 is a diagrammatic view illustrating other channel shapes for the annular ring member 20 than that shown in Figure 2, one channel being superimposed on the other channel.

The annular channel shaped ring member 6 has an outside flange 7 rotatably fitted in flat 25 ring 8 and inside flange 9 fitted into flat ring 8 at 10. An outside ring 11 holds flange 7 against flat ring 8 with bolts 12 and an inside ring 13 holds inside flange 9 against ring 8 with bolts 14. The annular channel shaped ring member 6 is 30 provided with transverse impeller vanes or ribs 15, the ribs or vanes 15 dividing the channel shaped ring member 6 into compartments or segments 16. The ribs or vanes 15 have their outer edges extended to just clear flat ring member 8.

35 A pair of flat inlet valves 17 have the same shape as the transverse inside section of the annular channel shaped ring member and are hinged on pins 18 by hubs 19, the pins 18 being held in recesses between flat ring 8 and flange 40 20 held together by bolts 12 and 21. The clearance of the flat valve 17 is very small when in the channel 6 and the inlet port 22 is formed by inlet manifold 23. Adjacent the inlet manifold 23 is exhaust manifold 24 with outlet ports 25 45 formed thereby.

A shaft 26 is provided with a hub 27 mounted thereon and is provided with recesses 28 to receive resilient spring arms 29 to act as spokes having their outer ends recessed in lugs 30. The 50 lugs 30 are preferably integral with the back side of the channel shaped ring member 6. Cap members 31 hold the resilient spring spoke members 29 in position by bolts 32.

The annular channel shaped ring member 6 is 55 provided with cam members 33 preferably in-

tegral on the outer flange 7 to actuate the cam levers 34 mounted on inlet valve shaft 18. The valve lever 34 is rigid on the valve shaft 18 and the valve 17 is integral with hub 19 rigidly mounted on the shaft 18 for actuation thereof.

A roller bearing 35 is mounted in the hub 36 and supports the shaft 26, the hub being connected to the flat ring member 8 by bolts 14.

The improved fluid motor is designed to work with various types of liquid or gas pressure and two forms of timing on the cams for operating the inlet valves are illustrated to show that a variation is necessary for different forms of liquid and a wide range of speeds, the design of the cam or length thereof being made to suit the requirement of the application of the motor.

When it is desired to operate the motor a fluid under pressure is passed through each port 22 of an intake manifold 23 and normally opens the inlet valve hinged on hinge pin 18 to a vertical position where it is stopped by vertical lug 37. The fluid passes from the raised valve through the annular channel shaped ring member to the transverse impeller vane or rib 15, the fluid pressure moving impeller vane or rib 15 and annular channel shaped ring member for rotation on shaft 26 through resilient spring spoke members 29. As the impeller vane or rib approaches the outlet port 25 in exhaust manifold 24 the fluid pressure in the annular channel shaped ring member decreases and the inlet valve is easily closed by the cam 33 as it passes over the cam lever 34 thus closing the inlet port and allowing the impeller rib or vane to pass over the valve when closed. A single or plurality of ports, vanes and valves may be used according to requirements of size and horse power.

The resilient spring arms will take care of shock loads between the shaft and impeller vanes 15 and the channel shaped member may be made with other shapes than that shown in Figure 2 and Figure 5, the channel shape being varied if desired without departure from the present invention.

What I claim as new and desire to secure by Letters Patent is:

1. A fluid motor comprising a flat ring member, an annular channel shaped ring member, said annular channel shaped ring member having the open side of the channel shaped portion thereof closed by said flat ring member, an inlet port, an outlet port, said ports being in said flat ring member, a flat valve, a cam, said cam being on said annular channel shaped ring member, said flat valve being hinged to said flat ring member for closing said inlet port when

said cam passes over said valve, impeller ribs, said impeller ribs being transverse on and dividing said annular channel shaped ring member into compartments, said inlet valve being closed by said cam when one of said impeller ribs passes over said valve, and said annular shaped ring member being revolvable against said flat ring member.

2. A fluid motor comprising a flat ring member, an annular channel shaped ring member, said annular channel shaped ring member having the open side of the channel shaped portion thereof closed by said flat ring member, an inlet port, an outlet port, said ports being in said flat ring member, a flat valve, a cam, said cam being on said annular channel shaped ring member, said flat valve being connected to said flat ring member for closing said inlet port when said cam passes over said valve, vanes, said vanes being transverse on and dividing said annular channel shaped ring member into compartments, said inlet valve being closed by said cam when one of said ribs passes over said valve, and said annular shaped ring member being revolvable against said flat ring member by a fluid pressure.

3. A fluid motor comprising a flat ring member, an annular channel shaped ring member, said annular channel shaped ring member fitted against said flat ring member, said channel shaped ring member having the channel shape portion thereof opening toward said flat ring member, said flat ring member closing the open side of said annular channel shaped ring member, inlet ports, outlet ports, said ports being in said flat ring member, inlet valves, said inlet valves being hinged on said flat ring member, said valves closing said inlet ports when in the closed position, said inlet valves dividing said annular channel shaped ring member into compartments when in the opened position, ribs, said ribs dividing said annular channel shaped ring member into compartments, said valves closed on said inlet ports when said ribs pass over said intake ports, and said annular channel shaped ring member being fulcrumed to rotate on said flat ring member.
